PEDESTAL CHAIR

Maurice P. Burke, Gstaad, Switzerland, assignor to Bjorgensen, S.A., Fribourg, Switzerland

Filed Dec. 5, 1968, Ser. No. 14,802

Claims priority, application Great Britain June 10, 1968

Term of patent 14 years

Int. Cl. D6—02

U.S. Cl. D6—120

FIG. 1.

FIG. 2.

FIG. 4.

FIG. 3.

FIG. 1 is a front perspective view of a chair showing my design;

FIG. 2 is a front elevational view thereof;

FIG. 3 is a side elevational view thereof;

FIG. 4 is a rear elevational view thereof.

The chair is characterized by the specifically configured base in combination with the unitized chair element, all as shown.

I claim:

The ornamental design for a pedestal chair, substantially as shown and described.
